Attn:

UNITED STATES PATENT OFFICE.

JAMES KELLEY, OF NEW YORK, N. Y., ASSIGNOR TO KELLEY & CORWIN, OF NEWARK, NEW JERSEY, A FIRM COMPOSED OF JAMES KELLEY AND GEORGE F. CORWIN.

TOY DESK TELEPHONE.

Application filed August 5, 1922. Serial No. 579,909.

To all whom it may concern:

Be it known that I, JAMES KELLEY, a citizen of the United States, residing at New York, in the county of New York and State 5 of New York, have invented a new and useful Improvement in Toy Desk Telephones; and I do hereby declare the following, when taken in connection with the accompanying drawings and the characters of reference 10 marked thereon, to be a full, clear, and exact description of the same, and which said drawings constitute part of this application, and represent in—

Fig. 1 a view in rear elevation of a toy 15 desk-telephone embodying my invention.

Fig. 2 a view thereof in horizontal section on the line 2—2 of Fig. 1.

Fig. 3 a detached plan view of the receiver-hook member of the two-part mounting-clamp of the device.

My invention relates to an improved toy desk-telephone, the object being to produce a simple, durable, and pleasing toy simulating a telephone and constructed with particular reference to fewness of parts and convenience of operation.

With these ends in view, my invention consists in a toy desk-telephone having a two-part mounting-clamp, one member of 30 which carries the receiver-hook and the other member of which carries the telephone bell.

My invention further consists in a toy desk-telephone having a two-part mounting-clamp, one member of which is extended at 35 one end to form an integral receiver-hook and the other member of which carries the telephone bell.

My invention further consists in a toy 40 desk-telephone having certain details of construction and combinations of parts as will be hereinafter described and particularly pointed out in the claims.

In carrying out my invention, as herein 45 shown, I employ a transmitter 5 pivotally mounted upon a post 6 upstanding from a cap 7 applied to the upper end of a standard 8 having a base 9. A cord 10 connected at one end with the transmitter has its opposite end connected with a receiver 11 adapted to be removably inserted into and normally

supported by a receiver-hook 12 constituting an integral extension of one end of the rear member 13 of a two-part mounting-clamp, the complementary outer member 14 of 55 which mounts a self-contained bell 15 having a projecting operating-lever 16 and secured by a rivet 17 to the said clamp-member 14, which is upset, as at 18, to form a flat bearing for the bell. The projecting ends of the 60 clamp-members 13 and 14 are perforated for the reception of clamping-screws 19 by means of which two members of the clamp are gripped upon the standard.

As shown, the receiver-hook 12 and clamp-member 13 are cut from a single piece of sheet-metal which is then twisted upon its axis to the extent of 90° to bring the receiver-hook into the horizontal plane.

The several features herein shown and 70 described may be of any approved construction, so long as they answer the intended purpose. Thus, the transmitter 5 and receiver 11, instead of being of the non-electric diaphragm type, might be dummies of the 75 electric type, either form of transmitter and receiver being equally applicable for use in a toy desk-telephone with my improved two-part mounting-clamp, one member of which is provided with a receiver-hook.

I claim:

In a toy desk-telephone, the combination with a base of a standard rising therefrom, a transmitter surmounting the standard, a receiver connected by a cord with the toy, a 85 two-part mounting-clamp applied to the upper portion of the standard, a self-contained bell, furnished with an operating-lever, mounted upon one part of the clamp, and a receiver-hook forming an integral extension of one end of the other part of the 90 said two-part clamp and bent at a right angle to the plane of the said part, so as to lie in the horizontal plane.

In testimony whereof, I have signed this 95 specification in the presence of two subscribing witnesses.

JAMES KELLEY.

Witnesses:

A. M. STARR,
JOHN F. SULLIVAN.
